UNITED STATES PATENT OFFICE.

WILLIAM L. DALY, OF SCHENECTADY, NEW YORK.

TAG-HOOK.

1,107,910.

Specification of Letters Patent. Patented Aug. 18, 1914.

Application filed June 1, 1912, Serial No. 700,961. Renewed February 4, 1914. Serial No. 816,529.

To all whom it may concern:

Be it known that I, WILLIAM L. DALY, a citizen of the United States, residing at Schenectady, in the county of Schenectady, and State of New York, have invented new and useful Improvements in Tag-Hooks, of which the following is a specification.

This invention relates to tag hooks, the object in view being to provide a device of this character which is especially designed for use in connection with tags having brass or metal eyes therein, the tag hook being particularly adapted for the purpose of permitting such tags to be easily connected to and disconnected from the hook, without mutilation of the tag.

With the above and other objects in view, the invention consists in the construction, combination and arrangement of parts, as will be hereinafter more fully described, illustrated in the accompanying drawings, and pointed out in the claim hereunto appended.

In the drawings: Figure 1 is a side elevation of a tag hook constructed in accordance with the present invention. Fig. 2 is an edge view thereof taken at right angles to Fig. 1.

The tag hook contemplated in this invention is constructed of a single length of wire 30 of any suitable gage, preferably hard or spring wire being employed. The wire is bent to form the hook 1 proper, which is provided with the upwardly extending bill 2, the extremity of which is outwardly deflected or curved, as shown at 3, to facilitate entering the eye of the tag upon the hook and releasing the same therefrom. After the formation of the hook 1, the wire is bent to form an upwardly extending shank or back 4, at the upper end of which the wire is formed into one or more spring coils 5 for giving the proper spring action to the guard 6 which extends downward from the coil 5 behind the bill of the hook. After forming the guard 6, the terminal portion of the wire is bent into the form of a single coil or eye 7, forming a rounded bearing surface which presses against the rounded inner face of the bill of the hook, as clearly shown in Fig. 1, thus greatly facilitating the entrance and exit of the tags.

After the formation of the single coil or

eye 7, the terminal portion of the wire is bent at a right angle to form a supplemental guard extending transversely of the space 55 between the shank and the first mentioned guard and is then extended laterally outward to form a thumb piece 8 adapted to be grasped by the thumb of the operator, in order to move the guard away from the bill 60 of the hook to more readily remove the tag, without tearing the latter. The supplemental guard is arranged at one side of the plane of the shank 4 and prevents the tags from getting between the shank and main 65 guard to interfere with the spring action of the main guard.

In placing the tag upon the hook, it is only necessary to pass the eye of the tag over the extremity of the hook and force the 70 same downward past the coil 7, the coil snapping back behind the tag against the bill of the hook. In order to remove the tag, the back or shank 4 of the hook and the laterally extending thumb piece 8 are grasped 75 between the thumb and forefinger of the left hand, and the coil 7 is moved away from the bill of the hook sufficiently to allow the eye of the tag to move outwardly over the extremity of the hook, without mutilating the 80 tag.

What is claimed is:

As an article of manufacture, a tag hook made of a single length of wire and comprising an upturned hook proper having the 85 bill thereof deflected outwardly to form a convex inner face, a shank extending upwardly from the back of the hook, a spring coil at the top of the shank, a guard extending from said coil downwardly between the 90 shank and bill, a complete coil at the lower extremity of the guard resting against the convex face of the bill, a backwardly extending supplemental guard extending transversely of the space between the shank and 95 first named guard, and a laterally projecting thumb piece at the extremity of said supplemental guard.

In testimony whereof I affix my signature in presence of two witnesses.

WILLIAM L. DALY.
